H. W. TAYLOR,
TUBE SCRAPER.
APPLICATION FILED SEPT. 16, 1919.

Patented Nov. 25, 1919.

FIG. 1.

FIG. 3.

FIG. 2.

*Inventor
Herbert W. Taylor*

By Attorney

UNITED STATES PATENT OFFICE.

HERBERT WILLMOTT TAYLOR, OF SUNNYSIDE, PHOENIX, MAURITIUS.

TUBE-SCRAPER.

1,323,123.

Specification of Letters Patent.

Patented Nov. 25, 1919.

Application filed September 16, 1919. Serial No. 324,195.

To all whom it may concern:

Be it known that I, HERBERT WILLMOTT TAYLOR, a subject of the King of England, residing at Sunnyside, Phoenix, in the colony of Mauritius, have invented new and useful Improvements in Tube-Scrapers, of which the following is a specification.

This invention relates to tube scrapers having rotary cutting members.

10 In apparatus in which liquids are treated while passing through tubes, scale and other matters contained in the liquid separate from it, and deposit in a more or less hard state upon the surface of the tubes. As 15 is well known it is very frequently difficult if not impossible to remove such scale or matters by the use of tools, without injury to the surface of the tubes, which, when such tubes are of brass, copper, and other 20 like metals, especially if they are thin, is very undesirable.

The object of this invention is, primarily, to provide an improved scraping or removing tool or appliance of the kind 25 specified by which the removal of such scale or deposited matters can be readily effected, without injury to the tube surface.

This instrument or scraper comprises rotary toothed tools, the active surface or 30 teeth of which are pointed; and in one arrangement two sets of such tools may be employed on a carrier, each set comprising a pair of toothed wheel cutters with oppositely arranged teeth, so that the teeth act 35 at two points, on each side of the diameter of the tube. The toothed tools or cutters are supported on axes one in front of the other, the axes being in the form of pins passing through the carrier.

40 Between these sets of cutters or rotary tools, there is employed an adjustable support, the pin or shank of which passes through and screws in and out of the carrier part; and in action the head serves 45 as a support to the body within the tube, and keeps it in the desired position in the tube, so that it acts as a positioning means to the tools in relation to the surface of the tube.

50 The scraper, the nature of which has been

above described, is illustrated in the accompanying drawings, in which Figure 1 is a side elevation, Fig. 2 is a plan, and Fig. 3 an end view.

In the drawings, 1 is the carrier or body 55 of the instrument, 2 are the rotary toothed tools, and 3 the support for holding the body with the tools in engagement with the tube surfaces. 4 represents the tube.

The tools 2, a pair of which are mounted 60 on the carrier on each side of the support 3, are mounted on pins 5, which pass through the carrier 1; and the support 3 screws in and out of the carrier or body 1, and is actuated and set by a handle 6.

65 It will be noted that the axis of the support 3 is at right angles to the axis of the cutter 2, which may be assumed to be of hardened tool steel.

When the scraper is used, the support 3 70 is set so that the points of the teeth of the tools 2, touch the surfaces of the scale of the tube. The scraper is then moved along the tube backward and forward by means of a hand actuating rod 7 screwed into one 75 end of it; and by adjusting the support 3 the cutting tools can be forced into firmer contact with the scales and the whole tube surface can be acted upon, and the scale removed. The teeth of the tools 2 when 80 formed as shown in the drawing, very effectively pierce the scale and crack it off, and in this way the effects and results above specified are accomplished.

In some cases, in lieu of the adjustment 85 causing the tools to bear on the surface of the tube being affected as above described and shown, the support 3 may have an enlarged head on it, with a rubber washer between its under side and the surface of the 90 carrier 1, and so arranged that this rubber would be under compression when the scraper is inserted in a tube, and by its resiliency the pressure of the tools upon the tube surface is produced.

95 What is claimed is:—

1. A flue cleaner consisting of a body portion, with a pair of rotary cutting tools mounted thereon and each projecting from opposite sides thereof, and a support ad- 100

justable in said body portion transversely thereof and between said cutting tools.

2. A flue cleaner consisting of a body portion with a pair of cutting tools mounted thereon and each projecting from opposite sides thereof, and a support adjustable in said body portion transversely thereof and between said cutting tools.

In testimony whereof I have signed my name to this specification in the presence 10 of two subscribing witnesses.

HERBERT WILLMOTT TAYLOR.
